[57] CLAIM

The ornamental design for a cigarette extinguisher, as shown and described.

DESCRIPTION

FIG. 1 is a front elevational view of the cigarette extinguisher showing my new design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof; and,

FIG. 7 is an exploded perspective view of the present invention.

In FIG. 7, the broken line showing of a cigarette is for illustrative purposes only and forms no part of the claimed design.
